UNITED STATES PATENT OFFICE.

ARPAD POLANSKY, OF DOUGLASTOWN, NEW YORK.

COMBINATION CARPET AND WINDOW CLEANER.

1,412,420.

Specification of Letters Patent. Patented Apr. 11, 1922.

Application filed October 7, 1921. Serial No. 506,147.

To all whom it may concern:

Be it known that I, ARPAD POLANSKY, citizen of Hungary, residing at Douglastown, in the county of Flushing and State of New York, have invented certain new and useful Improvements in Combination Carpet and Window Cleaners, of which the following is a specification.

This invention relates to a vacuum cleaner having combined therewith means for washing windows or the like.

The invention has for an object to provide a simple arrangement of parts whereby the device may be used as an ordinary vacuum cleaner or sweeper, or may be utilized to wash windows, or any other surfaces of relatively smooth configuration.

For further comprehension of the invention, and of the objects and advantages thereof, reference will be had to the following description and accompanying drawings, and to the appended claims in which the various novel features of the invention are more particularly set forth.

Fig. 1 of the drawings is a horizontal sectional view of a device embodying the invention, this view being taken on the line 1—1 of Fig. 2.

Fig. 2 is a longitudinal sectional view, taken on the line 2—2 of Fig. 1.

Fig. 3 is a detail longitudinal sectional view on the line 3—3 of Fig. 1.

As here shown my improved combination cleaning device comprises a circular casing 10 in which is a variable speed electric motor 11. In front of this casing 10 is an enclosed chamber 12 in which is a suction fan 13 driven by the motor 11. From this chamber 12 a short conduit 14 leads forwardly and downwardly to a transversely elongated, open-bottomed suction box 15. A yoked handle 16 is suitably hinged to the casing 10. The chamber 12 has an exhaust pipe 17 leading therefrom and adapted for connection to the usual bag. The device is supported by means of a pair of front wheels 20, suitably mounted in rearward offsets 21 from the ends of the suction box 15, and a rear castor wheel 22 central under the casing 10. The device as thus described is arranged for use as an ordinary vacuum sweeper.

The window washing means is as follows: Fixed to the rear end of the shaft of motor 11 is a bevel gear 25 meshing with a like gear 26 on a transverse shaft 27 on which is

a pulley 28 connected by a belt 29 with another pulley 30 on a short transverse shaft 31 suitably mounted in the suction box 15. The shaft 27 and belt 29 may be suitably enclosed as indicated at 32. Fixed on the transverse shaft 31 is a gear pinion 35 meshing with an elongated gear 36 fixed coaxially to a roller 37 of rubber or the like, having a rough peripheral surface arranged for detachable mounting in the suction box 15. As here shown this roller 37 has one trunnion 38 projecting through a suitable aperture in one end of the box 15, while the other trunnion 40 is supported in a short downward offset on the inner end of an angular slot 41 leading upwardly through the end wall of the box 15 from the bottom thereof. To hold this last mentioned trunnion in place I provide on the end wall of a box 15 a vertically slidable plate 42 whose lower end is provided with a semi-circular notch engaging the trunnion 40. This plate 42 has formed therein vertical slot 43 into which project a pin 44 and a bolt 45 fixed to the end wall of the suction box 15. The bolt 45 has a nut 46 threaded therein and adapted to be screwed against the plate 42 to releasably hold the latter in lowered, or operative, position. By unscrewing nut 46 the plate 42 may be raised to allow the trunnion 40 to be swung out of the slot 41 when the roller is to be removed.

I also preferably provide means whereby the roller is given an axial reciprocating movement and to this end the roller has an obliquely arranged peripheral groove 50 adjacent one end into which projects a finger 51 fixed to a rod 52 mounted in the box 15, behind the roller 37, for angular adjustment. As will be apparent, when roller 37 rotates, the engagement of the finger 51 in the groove 50 will impart an axial reciprocatory movement to the roller.

When it is not desired to impart a reciprocatory movement to the roller 37 rod 52 is rocked to free finger 51 from groove 50, and the roller is moved in one direction to its extreme position. Rod 52 is then further rocked until a second finger 54 thereon engages behind the end of the roller. To rock rod 52 it is provided with a projecting head 55, and to hold it in either adjusted position it has fixed thereto a hooked spring catch 56 adapted to engage in either one of a pair of holes 57 in the end wall of box 15. When the roller is used a suitable cleaning powder

may be sprinkled or rubbed thereon or on the window, or other surface being cleaned.

When the device is in use as a vacuum sweeper or cleaner, the roller 37 is removed 5 from the suction box and the device operated in the usual manner. When the device is in use as a window cleaner the handle 16 may be removed by springing the ends of its yoke off their attaching means, and a short fixed 10 handle 60 may be screwed into the back of the device.

Having thus described my invention what I claim as new and desire to protect by Letters Patent of the United States is as follows:

- 15 1. In a device of the class described, a suction box, means for exerting a suction therethrough, a roller adapted for removable mounting in said suction box, and means for 20 rotating said roller, and means for imparting an axial reciprocating movement thereto, said last means comprising a fixed element engaging in an oblique peripheral groove extending around the roller.
- 25 2. In a device of the class described, a suction box, a roller adapted for removable mounting in said suction box and having an oblique peripheral groove extending therearound, means for rotating said roller, a rod 30 in said suction box behind said roller and parallel thereto, and a pair of longitudinally and angularly spaced fingers on said rod one of which is adapted to engage in said groove

and the other to project across the end of the roller.

35

3. In a device of the class described, a suction box, a roller adapted for removable mounting in said suction box and having an oblique peripheral groove extending therearound, means for rotating said roller, a rod 40 in said suction box behind said roller and parallel thereto, and a pair of longitudinally and angularly spaced fingers on said rod one of which is adapted to engage in said groove and the other to project across 45 the end of the roller, and means for locking said rod in angularly adjusted positions.

40

4. In a device of the class described, a suction box, a roller adapted for removable mounting in said suction box and having an oblique peripheral groove extending therearound, means for rotating said roller, a rod 50 in said suction box behind said roller and parallel thereto, and a pair of longitudinally and angularly spaced fingers on said rod one 55 of which is adapted to engage in said groove and the other to project across the end of the roller, and means for locking said rod in angularly adjusted positions, said means comprising a hooked spring latch fixed to 60 said rod and adapted to engage in either one of a pair of apertures in the end of the suction box.

In testimony whereof I have affixed my signature.

ARPAD POLANSKY.
